UNITED STATES PATENT OFFICE.

ALEXANDER E. BLOCK, OF ST. LOUIS, MISSOURI, ASSIGNOR TO ALBERT KERN, OF ST. LOUIS, MISSOURI.

ARCH-SUPPORT.

1,043,058.

Specification of Letters Patent.

Patented Nov. 5, 1912.

Application filed September 25, 1911. Serial No. 651,030.

To all whom it may concern:

Be it known that I, ALEXANDER E. BLOCK, a citizen of the United States, and a resident of St. Louis, Missouri, have invented 5 certain new and useful Improvements in Arch-Supports, of which the following is a specification.

My invention relates to improvements in arch supports and has for its object to provide an arch support whose thickness may be regulated to conform with the requirements of the wearer, and whose thickness is adjustable forwardly and rearwardly as well as vertically.

15 In the drawings: Figure 1 is a perspective view of an arch support embodying my invention. Fig. 2 is a bottom plan view of the same. Fig. 3 is a transverse vertical view of the same in section. Fig. 4 is a 20 perspective view of the insert employed therein.

As shown in the drawings, I employ an insole 10, adapted to fit within a shoe and at the rear thereof, and of such a length 25 as to fit beneath the heel and arch of the foot of the wearer. Upon the lower face of the insole 10 I provide a flexible strip 11, which is sewed, or otherwise secured to the insole 10 along the line indicated by the 30 numeral 12, thus forming the pocket 13. Beneath the strip 11 the strip 14 is secured in like manner to form the pocket 15. Beneath the strip 14 is similarly secured the strip 16, forming the pocket 17; and beneath 35 the strip 16 is similarly secured the strip 18 to form the pocket 19. These pockets 13, 15, 17 and 19 are so formed as to be located beneath the arch of the foot of the wearer, the rear wall or edge of the pocket 40 19 being somewhat to the rear of the corresponding edge of the pocket 17, and the rear edge of the pocket 17 being slightly to

the rear of the rear edge of the pocket 19. The uppermost pocket 13 is of greater length than either of the pockets 15, 17 and 19. In 45 order to build up the support I employ one or more of the inserts 20, which are of any desired length, breadth and thickness which can be accommodated by either of the pockets 13, 15, 17 or 19; the insert being 50 made of a thickness to conform with the arch of the foot of the wearer, and the insert being located toward or away from the heel of the wearer to meet the requirements of his foot, whether such requirements are 55 due to the natural formation of the foot, or to an unnatural and abnormal condition of the arch due to accident or disease. The insert 20 will be made thickest at its rear portion, therefore, when it is desired to 60 support the anterior arch of the wearer's foot, and the entire support may be built up by employing two or more of the inserts 20 in different pockets or the same pocket, and the total thickness of the support may 65 be varied at will to accommodate different conditions of the same foot, or to accommodate the feet of different wearers.

Having thus described my invention, what I claim as new, and desire to have secured 70 to me by the grant of Letters Patent, is

In an arch support, the combination of an insole; an insert; and a plurality of overlapping pockets formed upon the lower 75 face of the insole, the highest points of the pockets being at various positions with reference to the length of the insole.

In testimony whereof, I have signed my name to this specification, in presence of two subscribing witnesses.

ALEXANDER E. BLOCK.
